UNITED STATES PATENT OFFICE.

JENS PETER HANSEN, OF COPENHAGEN, DENMARK.

MAGNESIUM-LAMP FOR PHOTOGRAPHIC USE.

1,315,118.

Specification of Letters Patent.

Patented Sept. 2, 1919.

Application filed September 5, 1918. Serial No. 252,761.

To all whom it may concern:

Be it known that I, JENS PETER HANSEN, manufacturer, a subject of the King of Denmark, and residing at No. 10 Jacoby's alli, 5 Copenhagen, Denmark, have invented certain new and useful Improvements in Magnesium-Lamps for Photographic Use, of which the following is a specification.

My invention concerns a magnesium-lamp 10 for photographic use, and in which, for ignition of the light-producing powder, is used an ordinary match, which is struck against a general striking composition.

Lamps of this kind are already known, 15 but these are rather large and complicated, likewise as they are not reliable in use nor free from danger.

By the present invention it has been endeavored to meet these inconveniences. The 20 lamp is further collapsible, so that it may be carried in the pocket.

On the drawing is shown some forms of execution of the invention, but it should expressly be mentioned, that the characteristic 25 features of the invention consists in the placing and displacement or turning of the match; while all the other parts of the mechanism may be varied in many different ways.

On the drawing Figure 1 is a form of the 30 outfolded lamp in side view.

Fig. 2 is a detail of the match-holder.

Fig. 3 shows the lamp in top view and,

Fig. 4 shows another form of the lamp seen from the side.

Fig. 5 is a perspective view of the handle 35 and of the placing of the match-holder.

Fig. 6 shows the placing of the match in the striking-composition.

The lamp itself consists of a plate 1, which 40 is horizontal when in working position, with a bent rear edge 2, upon which the back plate 3, which is vertical when in working position is applied in hinged manner and kept fast in the outfolded position by a pair 45 of leaf-springs 4.

The front part 5 of the plate 1 is offset and provided with an upstanding outer edge 6. In the middle of the member 5 is pressed 50 down a tongue 7, so that by this tongue and the surrounding edges of the member 5 there is formed a holder, which may be of a springy character.

On the underside of the plate 1 near the rear edge 2 is a loop or socket 8 for engagement with the handle 14—15, and across the 55 upper side of the plate lies a matchholder 9,

which is, in the form of execution now in question, square, and arranged in such a manner, that it may travel through a corresponding hole in the rear-edge 2. The 60 holder 9 has a hole 10, which extends entirely through the same to permit of cleansing and a screw 11 for holding the match in the hole. The rear-end of the holder 9 has a cylindric neck 12 and a head 13, which has 65 rectangular form.

The handle consists of a V-spring, the two branches of which are marked 14 and 15. The upper part of the branch 15 has a bending 70 16, which passes through a slot, formed by the branch 14, after which the end of the bending 16 has a bending 24, while the outer end is arranged to coöperate with the hoop 8, so that the plate 1 is held securely on the handle. 75

The upper end of the branch 14 is likewise bent, and forms a slot for the head 13 of the match-holder 9.

The branches 14 and 15 have a pair of finger plates 17 in order to facilitate the 80 manipulation of the handle.

The apparatus operates in the following manner:

The plate 3 is raised so that the holding springs 4 keep the plate in the vertical position. The holder 9 is pushed back, and the slot on the branch 14 is engaged with the head 13, by holding the handle in a horizontal position. When the head 13 has been passed through the slot, so that the branches of the 90 latter embrace the neck 12, the handle is turned to the vertical position, and the end of the branch 16 is pushed into the hoop 8. This position is shown on Figs. 1 and 3. 95

Now a piece of bent striking-composition 18 is applied between the tongue 7 and the plate 5 of the holder, and the composition-free end of a match 19, is introduced between the two pieces of the striking-composition, and then pushed into the match 100 holder 9, and clamped therein by the screw 11. Light-producing powder is then applied on the plate 1 above and around the holder 9, and in such a manner, that no powder is required on the place where the match 105 19 leaves the pieces of the striking composition 18.

The apparatus is now ready for use, and when, the branches 14 and 15 are pressed together, or rather, that the branch 14 is 110 pressed up against the branch 15, the match holder will be drawn out and the head of

the match 19 will be drawn from between the striking-composition 18, which squeezes around the head in a spring-like manner and as the match catches fire, it will at the same time ignite the powder lying on the plate 1.

When the apparatus is not used, the handle 14—15 is removed, and is together with the match holder 9, applied on the plate 1, after which the plate 3 is folded down over the same. The whole apparatus thus takes up only a small room, and is easily transportable.

Instead of the head 13 other means of connection between the holder and the spring-branch 14 may be used.

In Fig. 4 is shown a different form of means for the moving of the match-holder 9, which has here, outside the back plate 3, a head 13, but this co-operates here with a pin 20, which by a Bowden release 21 in connection with a press-knob 22 and corresponding handle 23, so that the pin 20 may be pushed forward which movement is transferred to the head 13, and therefrom to the match-holder. By this arrangement the handle 14—15 is made superfluous, and the lamp may then be worked at a distance, as the Bowden release may be given a length of several meters. Besides, the lamp may be arranged to be used with the handle when using the Bowden release, and the Bowden release may be arranged to draw instead of to push, its front parts (the wire and the end of the spiral) being then fastened respectively to the head 13 of the match holder and to an elongation upward of the handle-branch 15.

As well by the use of handle as of Bowden release this lamp is absolutely free from danger, as it is free from the springs now in use, which should be set before the use and the releasing of which may happen unintentionally and untimely. Likewise a failing is excluded (a good composition on the match-supposed) owing to the striking-composition squeezing the match during the pulling out.

As a modification should be mentioned that the match-holder needs not necessarily to be displaced, but may be arranged swinging around a fixed point, so that the match is ignited by swinging on above or between the striking composition.

For executing this movement the same transmission organs as above described may be used.

Having now described my invention what I claim as new and desire to secure by Letters Patent is:

60 1. A magnesium lamp for photographic

use, comprising a lamp body, a slidable match holder mounted on the body, two igniting surfaces removably secured to the lamp body in front of the match holder and between which a match extends, and means 65 for sliding the match holder.

2. A magnesium lamp for photographic use, comprising a lamp body, a slidable match holder mounted on the body, two igniting surfaces carried by the body in front 70 of the match holder and between which a match extends, and a handle secured to the lamp body and having a movable member engaging the match holder to slide the same.

3. A magnesium lamp for photographic 75 use, comprising a lamp body, a match holder slidably mounted on the body and having one end projecting through the same, two igniting surfaces carried by the lamp body and between which a match extends, and 80 an approximately V-shaped spring handle, having one member secured to the lamp body and the other to the projecting end of the match holder.

4. A magnesium lamp for photographic 85 use, comprising a lamp body formed of members hinged together to fold upon one another, a match holder slidably mounted on the body and having one end projecting through the same, two igniting surfaces carried by the lamp body in front of the match holder and between which a match extends, and an approximately V-shaped spring handle having one of its members detachably secured to the lamp body and its other end 95 detachably secured to the projecting end of the match holder.

5. In a magnesium lamp for photographic use, a lamp body having a socket in its bottom, a match holder slidably mounted on the body and having one end projecting through the same and provided with a head on said end, and an approximately V-shaped spring handle, one member being bent so as to engage the socket of the lamp body and 100 the other member provided with a slot for engaging the head of the match holder.

6. In a magnesium lamp for photographic use, a lamp body having an offset and a tongue in its base, a match holder mounted 110 to slide on the base in rear of the offset, and an igniting surface formed of a piece of material bent and held by the tongue in front of the match holder.

In testimony whereof I affix my signature 115 in presence of two witnesses.

JENS PETER HANSEN.
